UNITED STATES PATENT OFFICE.

ALFRED WENDT, OF FRESNO, CALIFORNIA.

CASTING DEVICE FOR MAKING BAND AND OTHER RINGS AND PARTS THEREOF.

1,323,938.

Specification of Letters Patent.

Patented Dec. 2, 1919.

Application filed October 1, 1918. Serial No. 256,402.

To all whom it may concern:

Be it known that I, ALFRED WENDT, a subject of the Emperor of Germany, residing at Fresno, in the county of Fresno and 5 State of California, have invented certain new and useful Improvements in Casting Devices for Making Band and other Rings and Parts Thereof, of which the following is a specification.

10 This invention has reference to a casting device for making band rings or rings of other styles and may be used for other purposes.

The object of the invention is to simplify 15 the production of rings, which, for simplicity of expression, will be hereinafter designated as band rings without limiting the invention to such particular type of rings.

In accordance with the invention there is 20 provided a casting device composed of a base plate arranged to receive and temporarily hold the parts of a casting flask and the base plate is constructed to hold any one of numerous pattern plates, each containing a half pattern of the ring to be cast.

25 Associated with the pattern plate is a gate-producing pattern which may be utilized to lock the ring pattern plate on the base plate, the one pattern plate being sufficient for 30 both halves of the flask so that when the mold is completed and the two halves of the flask are brought together there is a mold of a ring of twice the thickness of the pattern. After the casting is done the gate 35 slug is removed and the ring is finished. The patterns may all have a standard internal diameter, say about No. 2½ of the ring gage, and the internal diameter of the cast ring may be increased by the use of a ring 40 stretcher.

The arrangement permits the use of a minimum number of parts, since the designations of the patterns relate more particularly to the weight and thickness of the 45 rings, the internal diameter of the rings when cast being all alike and the different diameters being subsequently determined by a ring stretcher.

The invention will be best understood 50 from a consideration of the following detailed description taken in connection with the accompanying drawings forming part of this specification, with the understanding, however, that the invention is not confined to any strict conformity with the 55 showing of the drawings but may be

changed and modified so long as such changes and modifications mark no material departure from the salient features of the invention as expressed in the appended 60 claims.

In the drawings:—

Figure 1 is a perspective view of a ring pattern and pattern plate.

Fig. 2 is a perspective view of the reverse 65 side of the structure shown in Fig. 1.

Fig. 3 is a perspective view of the pattern-supporting plate and carrier therefor.

Fig. 4 is a perspective view of the gate 70 pattern.

Fig. 5 is a plan view of the pattern-supporting plate, carrier, pattern plate and gate pattern all associated.

Fig. 6 is a section on the line 6—6 of 75 Fig. 5.

Fig. 7 is a perspective view of the structure shown in Fig. 5 with one half of the flask applied.

Fig. 8 is a perspective view of the half of 80 the flask shown in Fig. 7 after having been filled with sand and removed from the pattern.

Fig. 9 is a perspective view of the flask 85 complete.

Fig. 10 is a vertical central section 90 through the flask of Fig. 9, from side to side and showing the flask carried by a drip vessel.

Fig. 11 is a section on the line 11—11 of 95 Fig. 5.

Referring to the drawings, there is shown a plate 1, usually, though not necessarily, of rectangular shape, and this plate may be flat and quite thin. One edge 2 of the plate is beveled and the other edge is 95 provided with an entering slot 3 having the side walls beveled oppositely one from the other. One face of the plate 1 carries a pattern 4 representing one half the thickness of a band ring, but this pattern may represent one half the thickness of other types of rings or parts thereof, or even of other articles.

There is provided a suitable number of plates 1 each with a pattern 4 thereon, the patterns being all of the same internal diameter but differing in thickness and in height from the plate to correspond to different weights of finished rings. The opposite face of the plate 1 from that carrying the pattern 4 is utilized for designations 5 and 6 representing the number of the pattern 100 110

and the weight thereof, these designations having to do with the completed ring. In actual practice, it is customary to make the band ring models in six widths with each 5 width in seven different weights, these covering all that are ordinarily in use.

There is also provided a support 7 of any suitable size and shape but which may be quite small for convenience of handling and 10 may, if desired, be made of wood. Fast on the support or block 7 is a base plate 8 made fast thereto by screws 9 or in any other appropriate manner. The base plate is formed with or carries a raised portion 10 which, as 15 well as the base plate 8, may be of rectangular conformation, although such particular shape is not obligatory. The corner portions of the raised portion 10 have sockets 11 formed therein and near one end of the 20 raised portion 10 it is cut down to the level of the base plate 8 to provide a recess or receptacle 12 of a size to snugly receive the pattern plate 1. One edge 13 of the recess 12 is beveled to receive the beveled edge 2 25 of the pattern plate 1 and by overhanging such beveled edge 2 lock the corresponding portion of the plate 1 in the recess. Leading from the opposite edge of the recess 12 is an undercut groove 14 reaching to the adjacent edge of the raised portion 10. Both 30 ends of the groove 14 are open and that end which leads into the recess 12 is positioned to match the recess 3 in the plate 1, said recess 3 being correspondingly undercut.

35 There is also provided a gate pattern 15 tapering from one end toward the other and defining a semi-frusto cone. On the flat face of the gate pattern 15 is a longitudinal rib 16 undercut in conformity with the 40 grooves 3 and 14 so that the rib 16 will slide along the grooves 14 and 3 locking the gate pattern thereto and also locking the recessed end of the plate 1 in the corresponding portion of the recess or receptacle 12, the opposite edge of the plate 1 being then locked by 45 the undercut edge 13. In order to facilitate the handling of the gate pattern 15 it is provided at the larger end with a handle or manipulating ring 17 and the support 7 is 50 cut away, as shown at 18, to accommodate the ring 17 and permit the ready grasping of it by the fingers of an operator.

Adapted to the raised portion 10 are two flask sections 19 and 20, which sections may 55 be identical and each represent a half of a complete flask so that the description of one applies to the other. Each flask section is in the form of a frame which may be substantially rectangular, although any particular 60 shape is not obligatory and, in the showing of the drawings, the corners of the flask section have reinforcing enlargements 21, this being simply for the purposes of strength.

On each side of each flask section is a 65 semi-cylindrical projection 22 with external

screw threads 23 extending about the curved wall of the projection. At one end of each flask section is a passage 24 of a size to accommodate a corresponding portion of the gate pattern 15. At the other end of the 70 flask section is a semi-conical stud 25. The plane faces of the screw projections 22 and of the half stud 25 are flush with a corresponding face of the flask section, said face being the one designed to rest upon the 75 raised portion 10 of the base plate 8 which is made plane to receive the flask section. At the reinforced corners 21 of each flask section of the plane face thereof are diagonally disposed studs 26 and diagonally disposed sockets 27, the studs 26 being arranged in one diagonal of the flask section and the sockets 27 in the other diagonal thereof. In this manner a set of studs 26 will always engage in diagonally opposite sockets 11 of 80 the raised portion 10 of the plate 8 and the set of studs 26 on each flask section will always enter the set of sockets 27 of the other flask section. In this way the parts are automatically centered and held against displacement one relative to the other. 90

When it is desired to make a ring, a suitable one of the patterns is chosen and is placed in the recess 12 and locked therein by the gate pattern 15. Then one of the flask 95 sections is placed upon the raised portion 10, centering thereon because of the entry of the studs 26 in the corresponding sockets 11. The flask section is then filled with casting sand and pressed down, as is customary, 100 after which the flask is carefully lifted off leaving an impression of the ring pattern and gate pattern in the sand. The other flask section is then applied and filled and the two flask sections are brought together 105 and centered by the studs 26 and recesses 27, and clamp nuts 28, which, for convenience, may be in the form of wing nuts, are applied to the screw projections 22 which are then in matching relation. This fastens the 110 flask sections 19 and 20 together. The two half studs 25 then become in effect a single tapering stud which is inserted in a tapering hole 28a formed in a boss 29 centrally located inside of a pan or receptacle 30, the flask 115 being then in an upright position with the pouring gate leading to the ring portion of the flask uppermost. Molten metal is poured into the gate filling up the ring cavity and is allowed to cool and any metal which may 120 spill over is caught in the pan or receptacle 30 thus preventing waste, this being important in the case of precious metals such as gold. After the metal has cooled the flask is removed from the receptacle 30, the 125 wing nuts are unscrewed and the sand is loosened thus exposing a cast ring with the gate lug fast thereto. The ring is then finished by first removing the gate lug and taking off any roughness or any inequalities on 130

the ring itself, after which, the ring is subjected to the action of a ring stretcher to bring it to the desired internal diameter if need be.

5. What is claimed is:—

1. Casting apparatus for producing finger rings and other articles alike on opposite sides, comprising a pattern plate with a ring pattern in relief fast to one face of the plate and approximately one-half the width of the complete ring.

2. Casting apparatus for producing finger rings and other articles alike on opposite sides, comprising a pattern plate with a ring pattern in relief fast to one face of the plate and approximately one-half the width of the complete ring, and a bed plate with a recess of a size and thickness to seat the pattern plate.

20. 3. Casting apparatus for producing finger rings and other articles alike on both sides, comprising a pattern plate with a ring pattern in relief fast to one face of the plate and approximately one-half the width of the complete ring; a bed plate with a recess of a size and thickness to seat the pattern plate, and a pattern representing one-half of a gate and provided with means for locking the gate pattern to the bed plate and for locking the pattern plate when seated in the recess of the bed plate.

4. In casting apparatus for finger rings and the like, a flat plate having a ring pattern fast on one face of said plate and approximating one-half the width of the complete ring, a bed plate seating the first-named plate with one edge of the pattern plate beveled and the corresponding edge of the seat in the bed plate undercut to receive the beveled edge of the pattern plate, and means coactively related to the portion of the pattern plate remote from the beveled edge and to the bed plate on that side of the recess remote from the undercut portion of said recess to temporarily lock the pattern plate in the recess flush with the bed plate and with the ring pattern projecting in relief from the plane of the exposed faces of the pattern and bed plates.

50. 5. In casting apparatus for finger rings and the like, a pattern plate with a ring pattern in relief fast thereon and projecting for a distance representing approximately one-half the width of the complete ring, said plate having one edge beveled and provided with an entering slot at the opposite edge extending to the exterior of the ring pattern.

55. 6. In casting apparatus for finger rings

and the like, a pattern plate with a ring pattern in relief on one face representing approximately one-half the width of the completed ring, a bed plate with a seat for the pattern plate with matching portions of the pattern plate and seat in the bed plate shaped to interlock, and other matching portions of the pattern plate and bed plate having grooves adapted to aline when the pattern plate is seated in the bed plate, and a gate pattern representing one-half of the complete gate and provided with means for entering the grooves in the two plates to lock the ring pattern plate in the bed plate and to lock the gate pattern to the bed plate.

7. In casting apparatus for rings, a pattern plate with a ring pattern on one face representing approximately one half of the completed ring, a bed plate with a recess therein of a size to receive the ring plate, said recess having an undercut edge and the ring plate being beveled to lodge in the undercut with the plate seated in the recess, the bed plate and ring plate having matching undercut grooves, and a gate pattern representing approximately one half the casting gate and provided with an undercut longitudinal rib for lodgment in the matching undercut grooves.

8. In casting apparatus for rings, a pattern plate with a ring pattern on one face representing approximately one half of the completed ring; a bed plate with a recess therein of a size to receive the ring plate, said recess having an undercut edge and the ring plate being beveled to lodge in the undercut with the plate seated in the recess, the bed plate and ring plate having matching undercut grooves, and a gate pattern representing approximately one half the casting gate and provided with an undercut longitudinal rib for lodgment in the matching undercut grooves, and the casting gate pattern being of taper form and provided with a manipulating member at its larger end.

9. In a casting apparatus for rings, a substantially flat plate provided on one face with a ring pattern in relief representing approximately one half the width of a completed ring and the other face of the plate having designations identifying the ring pattern.

In testimony whereof I affix my signature.

ALFRED WENDT.
